(57) **CLAIM**

The ornamental design for a perforated taco shell, as shown and described.

DESCRIPTION

FIG. 1 is a perspective view of a perforated taco shell according to an embodiment of the present design; FIG. 2 is a front elevational view of the perforated taco shell, with the rear view being a mirror image thereof; FIG. 3 is a top view of the perforated taco shell; FIG. 4 is a bottom view of the perforated taco shell; FIG. 5 is right side elevational view of the perforated taco shell, with the left side view being a mirror image thereof; FIG. 6 is a perspective view of a perforated taco shell according to another embodiment of the present design; FIG. 7 is a front elevational view of the perforated taco shell of FIG. 6, with the rear view being a mirror image thereof; FIG. 8 is a top view of the perforated taco shell of FIG. 6; FIG. 9 is a bottom view of the perforated taco shell of FIG. 6; and, FIG. 10 is right side elevational view of the perforated taco shell of FIG. 6, with the left side view being a mirror image thereof.

The evenly-spaced broken lines shown in FIGS. 1–10 illustrate portions of the perforated taco shell that form no part of the claimed design. The dash-dot broken lines in FIGS. 1, 2, 6 and 7 illustrate the boundary of the claimed design that forms no part thereof.

1 Claim, 6 Drawing Sheets
